UNITED STATES PATENT OFFICE.

ADOLPH B. SCHRIER, OF PITTSBURGH, PENNSYLVANIA, ASSIGNOR OF ONE-THIRD TO CHARLES C. WILLIAMS AND ONE-THIRD TO CHARLES C. LANG, BOTH OF PITTSBURGH, PENNSYLVANIA.

BOTTLE CAP AND STOPPER.

1,054,458.

Specification of Letters Patent. Patented Feb. 25, 1913.

Application filed May 10, 1912. Serial No. 696,383.

To all whom it may concern:

Be it known that I, ADOLPH B. SCHRIER, a citizen of the United States of America, residing at Pittsburgh, in the county of Allegheny and State of Pennsylvania, have invented certain new and useful Improvements in Bottle Caps and Stoppers, of which the following is a specification, reference being had therein to the accompanying drawing.

This invention relates to a bottle cap and stopper, and more particularly to that type of bottle closure commonly known as the "Crown cap."

The primary object of my invention is to furnish a cap of the above type with simple and effective means whereby the cap can be removed from the neck or mouth of a bottle without resorting to the use of a separate implement, as the ordinary hook shaped cap removing device commonly used.

Another object of this invention is to furnish a cap with an integral opening device that can be easily and quickly shifted into position to pry or force a cap from the neck of a bottle.

A further object of this invention is to provide a cap and cap opening device that can be made from a single piece of material and consequently manufactured at a minimum cost.

A still further object of this invention is to provide a strong and durable cap removing device that can be safely used without a liability of the hands being injured or a bottle broken.

I attain objects by a mechanical construction that will be hereinafter specifically described and then claimed.

Reference will now be had to the drawing, wherein:

Figure 1 is a front elevation of a cap in accordance with this invention. Fig. 2 is a cross sectional view of the same, and Fig. 3 is a perspective view of the cap and the opening device thereof.

The reference numeral 1 denotes an ordinary cap that is shaped to be forced upon and held in engagement with the mouth or neck 2 of a bottle or other receptacle. The cap 1 has a depending crimped or scalloped annular flange 2 that frictionally retains the cap upon the neck of a bottle.

Formed integral with the flange 2 is an

opening device, comprising a depending bar 3 that is bent upon itself, as at 4 and the lower end thereof flared to provide a finger piece or hand grip 5. The flat side of the bar is radially disposed relatively to the center of the cap 1 and said bar has a web 6 at the edge of the flange 2, said web having a small slip or slot 7, which permits of the end of the bar 3 being bent upwardly to engage the flange 2, with the finger piece 5 extending outwardly in a plane horizontal 65 with the cap 1. The opening device is arranged between two of the crimps or scallops 8 of the cap 1 whereby the intermediate portion of the flange 2 can be slotted or slotted, as previously mentioned. With the 70 opening device in a horizontal plane with the cap 1 and the end of a bar 3 engaging the flange 2, a bottle can be held in one hand while the cap 1 is forced from the mouth or neck thereof. The bottle opening 75 device is made of a sufficient length whereby considerable leverage can be obtained for removing the cap 1, and with the opening device extending from said cap against the outer side of a bottle neck, it does not interfere with the bottle being handled or packed in the ordinary and well known manner. A gasket 9 made of cork or other material can be used in connection with the cap 1.

It is thought that the utility and convenience of a bottle cap in accordance with this invention will be apparent without further description, and I would have it understood that the structural elements are susceptible to such variations and modifications as fall 90 within the scope of the appended claims.

What I claim is:—

1. As a new article of manufacture comprising a crown cap having means for removing the same from a bottle neck, said 95 means consisting of a bar having each upper corner thereof formed integral with the crown thereby providing an opening between the bar and the cap, said bar having its upper portion bent longitudinally upon 100 itself thereby providing a free edge disposed at right angles with respect to the cap, said free edge adapted when the bar is raised to engage the cap for removing the latter from a bottle neck.

2. As a new article of manufacture, a crown cap provided with means for removing the same from a bottle neck, said means

consisting of a bar depending from the cap and including a free upper edge disposed at right angles with respect to the rim of the cap, and providing means to engage the rim 5 of the cap when the bar is raised to remove the cap from a bottle neck.

3. As a new article of manufacture, a crown cap provided with means for removing the same from a bottle neck, said means 10 consisting of a bar depending from the cap and including a free upper edge disposed at right angles with respect to the rim of the cap, and providing means to engage the rim of the cap when the bar is raised to remove 15 the cap from a bottle neck, said bar having its lower portion constituting a finger piece.

4. In combination a crown cap, a bar having its upper portion bent longitudinally upon itself, each of said bent portions having its inner corner integral with the cap, 20 said bent portions disposed at right angles with respect to the cap and providing means when the bar is raised to engage the rim of the cap to remove the latter from a bottle neck, the lower portion of said bar constituting a finger piece. 25

In testimony whereof I affix my signature in the presence of two witnesses.

ADOLPH B. SCHRIER.
